UNITED STATES PATENT OFFICE

LANSING ONDERDONK, OF CHICAGO, ILLINOIS, ASSIGNOR TO THE UNION
SPECIAL SEWING MACHINE COMPANY, OF SAME PLACE.

DESIGN FOR A SEWING-MACHINE FRAME.

SPECIFICATION forming part of Design No. 22,837, dated October 17, 1893.

Application filed September 25, 1893. Serial No. 486,487. Term of patent 14 years.

To all whom it may concern:

Be it known that I, LANSING ONDERDONK, a citizen of the United States, residing at Chicago, in the county of Cook, State of Illinois, have invented a new and original Design for Sewing-Machine Frames, of which the following is a description, reference being had to the accompanying drawing, and to the letters of reference marked thereon.

10 My invention relates to a new and original design for a sewing machine frame.

The invention is illustrated in the accompanying drawing which shows a perspective view of a sewing machine frame embodying 15 the design.

The base of the frame is shown at A. This is approximately square at the bottom with the exception that the forward side *a* is curved outward slightly. Rising from the bottom 20 part A and set in from the edge thereof upon two sides is the standard B formed as shown with the curved portion *b* and the perpendicular portion *c*. At the point *d* the pedestal is narrowed longitudinally having a squared 25 portion *e*.

From the point where the perpendicular portion *c* ends the arm or goose-neck commences consisting of the vertical part C, curving inwardly from the base, (but having 30 a slight bulging portion *f*,) gradually con-

tracting in size on all sides for a short distance, then again growing larger, the line of contraction and expansion being a concave 35

curve which on the inside merges into and forms the outline of the lower edge of the horizontal portion D. This horizontal portion D is convex on its upper surface and said portion gradually diminishes in size toward the end, but just before the end is reached enlarges into the web *g* with the projecting lugs shown. The bed plate E is in general of 40 cylindrical shape. At its rear end it is squared and has rounded corners F. Upon its under side at the end a squared portion *h* projects downwardly and from the center of the end portion a web *i* formed on a concave curve *k* 45 also projects downwardly, the parts *h* and *i* being united by the part *l* resting on the part *e* of the standard. From the rear end of the bed plate by sharp concave curves it tapers into the form shown, being of cylindrical 50 shape to the point *m* whence it begins to taper to the point *n*, the end of said bed plate being in the shape of the frustum of a cone.

Having thus described my invention, what I claim, and desire to secure by Letters Patent, is—

The design for a sewing machine frame, substantially as shown and described.

In testimony whereof I affix my signature in presence of two witnesses.

LANSING ONDERDONK.
